TUBULAR INTERLOCKING PILING

Edwin Fenton Stevens, St. Paul, Minn.

Application January 31, 1936, Serial No. 61,712

2 Claims. (Cl. 61—53)

My invention relates to piling and particularly to tubular interlocking piles.

Steel sheet piling is often used in constructing, permanent or temporary, cofferdams, walls, dams, bridge piers and abutments, culvert walls, foundations and other types of walls where relatively strong and/or watertight construction is required.

An object of my invention is to provide an interlocking tubular steel pile capable of use in constructing a wall having great strength and rigidity.

This and other objects and advantages of the invention will be more fully set forth in the following description made in connection with the accompanying drawing, in which like reference characters refer to similar parts throughout the several views, and in which

Fig. 1 is a top plan view of one form of my tubular piling;

Fig. 2 is a top plan view of a second form of my tubular piling;

Fig. 3 is a partial vertical view of a wall made of units such as shown in Figs. 1 and 2;

Fig. 4 is a top plan view of a third form;

Fig. 5 is a top plan of a fourth form;

Fig. 6 is a top plan view of a corner forming unit for use with units such as that shown in Fig. 1, and

Fig. 7 is a top plan view of a fifth form of my pile unit.

Referring to the drawing, the form of my tubular piling shown in Figs. 1 and 3 consists of an elongated member 6 of circular tubular cross section having a pair of interlocking elements 7 extending longitudinally thereof and secured to diametrically opposite sides thereof. Each interlocking element 7 has a pair of mounting flanges 7a formed integrally therewith and secured to the tubular member 6 by suitable means such as welding or the rivets 8. The two pieces each comprising an interlocking element 7 and a pair of mounting flanges 7a are similar and are secured to the tubular member 6 with respectively opposite ends up.

The form of my pile shown in Fig. 2 is similar to the form shown in Fig. 1 with the exceptions that the tubular member 9 is of generally oval cross section and the interlocking elements 10 are situated at positions corresponding to the ends of the longest diameter of the member 9, are formed integrally with, welded to or otherwise secured to the member 9 and are disposed with respectively the same ends up. In driving this form of pile to form a wall all of the pile units are driven with the same end up.

The form of my pile shown in Fig. 4 is similar to the form shown in Fig. 3 with the exception that the interlocking elements 11 are situated in positions corresponding to the ends of the shortest diameter of the tubular member 12.

The form of my piling illustrated in Fig. 5 consists of an elongated tubular member 13 of generally circular cross section but having portions of the wall thereof at diametrically opposite points bent inwardly to form a pair of diametrically located generally rectangular grooves or recesses extending longitudinally of the member 13. An interlocking element 14 extends longitudinally of each recess and is secured to the portion of the tubular element 13 forming the bottom of the recess by suitable means such as welding or being formed integrally therewith. The two interlocking units 14 of each pile are attached to the tubular element 13 with corresponding ends up. The depths of the recesses are so dimensioned that facing portions of adjoining piles in a wall formed thereof will abut each other, as shown, when interlocking elements 14 of these adjoining piles are placed in interlocking relation. Thus a wall formed of such piles will have corrugated sides and the interlocking elements 14 will be enclosed except at their ends.

To provide for producing corners or angles in a wall formed of the pile units illustrated in Fig. 5, an elongated tubular member 15, formed in the same manner as the member 13 and being provided with interlocking elements 14 in the same way, is used. However, the interlocking elements 14 of the tubular member 15 are spaced apart circumferentially of the member 15 by an angle 35 of 90 degrees, as shown, or any other desired angle instead of being diametrically opposite each other.

Fig. 6 shows a pile unit which is similar to the unit shown in Fig. 1 except that the interlocking elements 16 thereof are welded to or formed integrally with the tubular member 17 thereof instead of having a base riveted to the tubular member. Fig. 6 also shows a pile unit for use in forming corners or angles in a wall 45 built of the above described units of Fig. 6. The corner-forming unit is constructed in the same manner as the other units with the exception that the interlocking elements 18 thereof are spaced apart circumferentially of the tubular member 19 thereof by an angle of 90 degrees, as shown, or any other desired angle instead of being diametrically opposite each other.

Fig. 7 shows a form of my piling identical with the form shown in Fig. 6 except that the tubular 55

members 20 and 21 thereof are provided with pairs of interlocking elements 22 in place of the respective single interlocking elements 16 and 18 of the respective tubular members 17 and 18 of Fig. 6.

If desired the interiors of the tubular members of any of the above described forms of my piling may be filled with filling material 23 such as concrete, earth, sawdust, cinders or other material as indicated in Figs. 1, 2, 5, 6, and 7. The recesses or grooves in which the interlocking elements of the form of Fig. 5 are disposed may be filled with filling material 23 as indicated in Fig. 5. Filling with material 23, as described, of course increases the strength of a wall made of my pile units.

In all of the above described forms of my piling, great strength is obtained through the use of tubular construction in the same. Walls 20 made from a plurality of my piling units are driven in the same manner as ordinary steel sheet piling but provide substantially a double wall.

It is apparent that I have invented novel and improved steel piling having a tubular form giving the same great rigidity and strength.

It will, of course, be understood that various changes may be made in the form, details, arrangement and proportions of the parts, without departing from the scope of my invention, which, generally stated, consists in a device capable of carrying out the objects above set forth and in the novel parts and combinations of parts disclosed and defined in the appended claims.

35 What is claimed is:—

1. A tubular pile unit comprising an elongated tubular member, a portion of one side of

said tubular member being displaced inwardly to form a groove extending longitudinally of said member, an interlocking element attached to said tubular member and projecting therefrom and disposed at least in part in said groove and a second interlocking element attached to said tubular member and projecting therefrom and extending longitudinally of said member in circumferentially spaced parallel relation to said groove, said interlocking elements being situated at such respective radii from the longitudinal axis of said member that, when two such members are connected by interlocking one interlocking element of one member with the other 15 interlocking element of the second member, the facing sides of the respective members will be substantially in abutment with each other and said interlocking elements will be concealed.

2. A tubular pile unit comprising an elongated 20 tubular member having a pair of continuous circumferentially spaced radially disposed longitudinal grooves therein, interlocking elements attached to said tubular member and projecting therefrom radially into said grooves, the interlocking elements of the tubular member being so arranged that when two such members are connected, one interlocking element of one member will engage with one interlocking element of the other member to bring the facing sides of 30 the two tubular members into contact adjacent the grooves wherein the engaging interlocking elements extend thereby concealing the engaging interlocking elements and producing a multiple sealed joint between the adjacent members. 35

EDWIN FENTON STEVENS.
